UNITED STATES PATENT OFFICE

CONRAD SCHUMACHER, OF LYNNBROOK, NEW YORK, ASSIGNOR TO AUTO STROP SAFETY RAZOR CO. INC., OF NEW YORK, N. Y., A CORPORATION OF NEW YORK

METAL-ALIGNING DEVICE

Application filed July 16, 1926. Serial No. 122,779.

This invention has reference to improved means for supporting and aligning strips of metal while traveling lengthwise to maintain their edges in proper position or alignment for grinding or honing the edges, or both, and for keeping such edges from contact with undesired objects or parts of the machine that would injure the sharpened edges.

10 The invention comprises novel details of improvement that will be more fully herein-after set forth and then pointed out in the claims.

Reference is to be had to the accompanying drawings forming a part hereof, wherein

15 Fig. 1 is a plan view of a grinding or honing machine embodying this invention;

Fig. 2 is a vertical longitudinal section of the machine;

20 Fig. 3 is an enlarged detail plan view, partly in section, illustrating devices for maintaining the strip in alignment for grinding and/or honing its edges;

Fig. 4 is a section on line 4, 4, in Fig. 3;

25 Fig. 5 is a detail end view, partly broken away, looking from the right hand side of Fig. 3; and

Figs. 6 to 10 are detail views illustrating different positions of the supporting or aligning devices for the strip, illustrating a cycle of operations of such devices.

Similar numerals of reference indicate corresponding parts in the several views.

The numeral 1 indicates a frame which

35 may be of any suitable construction. At A is indicated a strip of metal, such as relatively thin steel, one or both of the edges of which are to be ground or honed, or both. Such strip is shown provided with spaced holes a. The strip A is adapted to be severed crosswise between certain of the holes a to produce safety razor blades after grinding or honing the strip, although the strip may be used for other purposes. The strip A may

40 be supplied in the form of a coil on a reel in well known way. At 2 are spaced guiding rolls at the receiving end of the machine, between which the strip A travels in the direction of the arrow in Fig. 1. Said rolls

45 are shown supported in a position with their

55 axes at an angle to the plane of the strip which travels, as illustrated, on edge, so that the operating surfaces of said rolls lie at an angle to the plane of the strip. As the strip is propelled between said rolls the latter, by contact with the strip, tend to keep the strip from rising and serve to force the strip downwardly against a flat guide 3 supported by the main frame, so that the lower edge of the strip will slide along said guide

60 with relation to grinding or honing rolls 4 located above the strip to grind or hone its upper edge, (Figs. 1 and 2). Pivots 5 for the rolls 2 extend at an angle to the plane of the strip and are carried by slidable blocks 6 which are shown forked to receive said rolls, which blocks are guided in ways 7 on support 8 on the main frame, (Fig. 2), springs at 9 between said support and the blocks 6 serving normally to press the rolls 2 against the strip A, (Fig. 1). Any suitable means

65 may be provided for propelling the strip A through the machine. In the example illustrated a pair of feed rolls 10 are journaled upon shafts 11, 11^a at the strip delivery end of the machine. The shaft 11 is shown provided with a pinion 12 in mesh with a pinion 13 on shaft 11^a, and shaft 11 is shown provided with a worm wheel 14 in mesh with a worm 15 journaled in bearings

70 provided with a sprocket wheel 15^a receiving chain 16 from drive sprocket 17 on drive shaft 18 journaled on the frame 1. Drive shaft 18 may be driven in any desired way. During rotation of said shaft the strip A will be propelled at a desired speed through the machine in the direction of the arrow in Fig. 2. During such propulsion of strip A the rolls 2 guide the strip and keep said strip with a downward tendency, as before stated. The rolls 4 are shown carried by shafts 19 journaled in supports 20 on opposite sides of the strip, which supports are

75 suitably carried by frame 1. The shafts 19 are shown provided with pulleys 21 which may be driven in any suitable way for rotating the rolls 4, such as by means of belt 22 operated by drive pulley 23 on the main shaft, (Figs. 1 and 2). Where the strip is

80

85

90

95

100

to be ground or honed on opposite edges a second pair of rolls 4^a are provided in spaced relation to the rolls 4 and carried by corresponding shafts 19^a shown supported and operated in manner described with respect to rolls 4, as by means of pulleys 21^a, belt 22^a and drive pulley 23^a, (Figs. 1 and 2). The means above described are illustrative of a construction whereby the strip A may be 10 propelled continuously and its edge or edges ground or honed, but it will be understood that the same are illustrative merely of a means for the purpose stated, since the improvements herein described may be used in 15 conjunction with any suitable grinding or honing means for a strip that is propelled during grinding or honing, or both. While the rolls 4 and 4^a have been referred to as grinding rolls it will be understood that they 20 may be of the variety known as honing rolls, or the machine may be equipped with the grinding rolls referred to and also with honing rolls disposed along the strip beyond the grinding rolls, in the direction of travel of 25 the strip, for honing its edge or edges after grinding the same.

In order to maintain the edge or edges of the strip A in proper position for operation thereon of the grinding or honing rolls 30 during travel of the strip, means are provided for supporting the strip with its sharpened edges out of contact with the machine. The means illustrated for such purpose are arranged as follows:—A guide 24 is supported 35 upon frame 1, as by uprights 25, and extends lengthwise of the machine, being shown provided with a guideway 24^a in which a slideable reciprocable member 26 is operative. The strip A passes through the guideway and 40 travels through a guiding slot 27 therein that has enlargements 27^a at its ends through which the sharpened edge or edges of the strip pass so as not to contact with the metal of the guide, (Fig. 5). The slide 26 at one 45 side of the strip A is shown provided with a dog 28 pivotally supported upon the slide at 29. The dog is provided with a nose or projection 28^a that is adapted to pass through a hole a in strip A. The nose or projection 28^a 50 is preferably tapered toward its extreme end for ready entrance into any hole a of the strip as the latter travels through the machine. The dog 28 is shown provided with an extending arm 28^b having a lateral projection 30 that extends into a guiding groove 31 in the extension or plate 24^b of guide 24. (Figs. 3 and 5.) The groove 31 may be milled in the metal of the plate 24^b and has a contour such as to cause rocking of dog 28, 55 as slide 26 travels, in proper timing to engage and release the strip A. The groove 31 has an inner edge 31^a, shown extending at an acute angle with respect to the plane of guideway 24^a, adapted to cooperate with the projection 30 for operation or tilting of dog 28

to cause its nose 28^a to enter a hole in strip A during travel of said strip in the direction of the arrow in Fig. 6, the groove 31 being relatively wide at 31^b adjacent to the edge 31^a for free play of projection 30 therein, (Figs. 3 and 6). From the inner termination of edge 31^a the edge 31^c of groove 31 extends substantially parallel with guideway 24^a in such a manner that the projection 30 will travel in said groove along the edge 31^c while the nose 28^a is in a hole in strip A, whereby the dog 28, and thereby the slide 26, will be propelled by and with said strip, (Fig. 7). The edge portion 31^d of groove 31 extends from edge 31^c at an angle in the direction away from guideway 24^a, so that when projection 30 passes from the adjacent end of edge 31^c it will travel away from guideway 24^a through the groove along edge 31^d, whereby the dog 28 may tilt to withdraw the nose 28^a from the hole in strip A, (Fig. 8). The lower portion 80 of the groove 31, and particularly its edge 31^e, inclines in a direction away from the plane of guideway 24^a from the edge 31^d so that when the projection 30 travels through the groove 31 along the edge 31^e the nose 28^a 85 will be entirely withdrawn from the hole in strip A to release the dog from said strip, (Figs. 9 and 10). The lower portion of groove 31 is in communication with the widened portion 31^b so that the projection 30 will be free at the angle where the edges 31^a and 31^e meet, so that the dog may rise from the lower portion 31^e of the groove, (Fig. 10), 90 into the upper widened portion 31^b thereof. The outer marginal edge portion of the groove 31 is of a suitable contour to maintain the projection 30 in cooperation with the inner edges of the groove during travel of the projection 30 to and fro or along the groove. 95 Adjacent to the edge 31^d is a finger 32, shown pivotally supported upon plate 24^b at 33 and normally drawn by a spring 34 against a stop 35 on said plate, (Fig. 6). The spring 34 is shown attached to the free end of finger 32 and to a stud or the like 36 on plate 24^b. The operative edge 32^a of finger 32 is inclined, substantially in the direction of the edge 31^d of groove 31, and normally lies in position to be encountered by the projection 30 100 when the dog 28 and the slide 26 are drawn by the strip A, (Fig. 3). The action of finger 32 in engagement with projection 30 is to assist the latter in traveling down the groove 31 along its edge 31^d to enter the lower part 105 31^e of said groove, and the edge portion 32^a of said finger will overlie the projection 30 and force the latter to enter the lower portion 31^e of said groove, (Fig. 9). At the end of groove 31 opposite the finger 32 is a finger 110 37, pivotally supported at 38 upon plate 24^b and normally drawn toward a stop 39 by spring 40, (Fig. 6). The spring 40 is shown attached to finger 37 and to a stud 41 on plate 24^b. The finger 37 has a suitably curved or 115 120 125 130

shaped outer edge 37^a adapted to cooperate with projection 30 of dog 28, (Figs. 3 and 10). A spring 42 is shown connected with or coiled around a stud 43 on plate 24^b, the short arm of said spring being attached to said plate by a stud 44. The long arm 42^a of spring 42 operates against slide 26, normally tending to push said slide in the direction opposite to the travel of strip A, with the projection 30 sliding through the portion 31^c of groove 31, (Fig. 9). The engagement of the projection 30 of dog 28 with the metal of the edge 31^c of groove 31 limits the movement of slide 26 by the spring 42 to the left in Fig. 10. Said projection will encounter the finger 37 and move the same laterally against the tension of its spring 40, so that when projection 30 enters the lower angle at the juncture of the part 31^c of groove 31 with the edge portion 31^e at the point 31^h, (Fig. 9), the projection 30 will be in a position to be pushed upwardly by the spring action of finger 37 into the upper widened portion 31^b of the groove 31, as illustrated at the left in Fig. 3. In such position of the parts the nose 28^a will encounter the strip A in case no hole in the strip opposes the nose, the dog 28 being then retained in a free position by the finger 37. When a hole in strip A registers with nose 28^a, due to the travel of the strip, said nose will enter said hole and the travel of the strip will cause the dog 28 with the slide 26 to advance, whereupon the projection 30 will engage the edge 31^a of groove 31 to force the nose 28^a farther into the hole in the strip, as before stated, (Fig. 7).

In order to assist the release of the nose 28^a from a hole in the strip A, after the projection 30 has reached the junction point between the edges 31^a and 31^c, (Fig. 3), an inclined or cam-like surface 45 is encountered by the nose. Since said surface is on the side of the strip A opposite the dog and inclines toward the strip A the nose 28^a will be forced along the hole in the strip toward the termination of the travel of the dog with the strip, (Fig. 8), and said projection 30 will be operated by the finger 32, since when projection 30, (being propelled by strip A), encounters edge 31^d of groove 31 said projection will push back the finger 32, (Fig. 3). During further progress of the strip the projection will pass along 31^a of the groove and the inclined edge 32^a of finger 32 will operate upon projection 30 to force it along the groove, (Fig. 8), to cause full withdrawal of the nose 28^a from the hole in the strip, (Fig. 9). The projection 30 next entering the portion 31^c of groove 31 will provide freedom to the slide 28 to be pushed along guideway 24^a by spring 42 to the position shown in Fig. 10, whereupon finger 37 will be engaged by the projection 30, with the nose 28^a entirely released from strip A for a succeeding operation, and so on as the strip travels along. The surface

45 is shown provided on a block 46 secured to the guide 24 by screw 47.

When the nose 28^a is in a hole in strip A said nose will serve to retain the strip in a definite plane so that the edges of the strip will not engage any material of the guides and will be retained in proper position for grinding or honing. In order that the strip may be maintained in the desired position when a nose 28^a is released from the strip at least two of the slides 26 with dogs 28 having noses 28^a and corresponding fingers 32, 37 and other associate parts are provided, (Figs. 1 and 3), which are so spaced as to operate alternately with respect to the holes in strip A. When one nose 28^a is in a hole of strip A the nose 28^a of the adjacent dog 28 will be free from the strip ready to engage the same when a hole *a* registers with such nose, whereby the noses 28^a will operate alternately in holes in the strip, so that at least one of such noses always will be in engagement with the strip to retain and guide the same as it travels through the machine. Such construction is illustrated in Fig. 3.

In Fig. 1 a pair of the dogs 28 and associate parts are illustrated at the left of rolls 4; another pair of such dogs are located at the left of rolls 4^a, and a further pair of such dogs are shown located at the right of the feed rolls 10, whereby the sharpened edges of the strip are maintained free from obstructions during travel of the strip along the machine. Any desired number of the dogs 28 and associate parts may be provided in the machine.

The strip is propelled continuously and the nose 28^a of dog 28 will normally bear against the surface of the strip when the dog is in the retracted position, such as at the left hand side of Fig. 3. When a hole *a* in the strip opposes said nose 28^a the nose will enter the hole and initially engage an edge of said hole, and the dog with its slide will be moved along by the strip, whereupon the projection 30 will engage the edge 31^a to cause the nose to gradually advance into said hole from the position shown in Fig. 6 to the position shown in Fig. 7. When the nose 28^a engages the cam-like surface 45 the continued travel of the dog with the strip will cause the nose to be pushed outwardly through hole and the projection 30 will engage the spring-acting finger 32 in such a way that when the projection 30 reaches the edge 31^d said finger will operate upon said projection to push the latter along said edge from the position shown in Fig. 8 to the position shown in Fig. 9. The nose 28^a will be entirely withdrawn from the hole in the strip as in Fig. 9, and the spring 42 will operate against slide 26 to push it toward the left in Fig. 9 to assume the position shown in Fig. 10, with nose 28^a released from the hole in the strip, ready for a succeeding operation as be-

fore described. With two slides 26 and corresponding dogs 28 and parts co-operating with the latter set in suitable spaced relation, one of such dogs will be in cooperation with the strip while the other dog is out of cooperation therewith, and so on alternately as the strip travels. During travel of the strip one or the other of the dogs 28 will engage the strip to support and align it in proper position respecting the sharpening devices so that the sharpened edges of the strip are maintained out of contact with any object that would tend to dull the sharpened edges.

The improvements described will serve to retain and align the edge of the strip A in proper position relatively to the adjacent or associate edge sharpening means, such as the rolls 4 or 4^a, so that they will operate upon the strip edge to grind or hone the same, or both, in an accurate way. A further advantage is that, since long thin strips of steel, such as adapted for the production of safety razor blades, are liable to be more or less non-straight, or what may be called wavy, the dogs 28, when their noses or projections 28^a are in the holes *a* of the strip, will serve to align the strip and cause its edge to be propelled in a substantially straight line respecting the sharpening rolls for desired operation of the latter upon the strip edge.

The strip aligning devices set forth are an improvement in the aligning devices disclosed in the application of H. J. Gaisman and C. Schumacher, filed May 1, 1924, Serial No. 710,270.

Having now described my invention what I claim is:—

1. Means for aligning a perforated strip of metal while traveling comprising means to propel the strip, a slide member, guiding means therefor, a dog movably carried by said member and provided with a nose to enter holes in said strip while it is traveling to support and align the latter, a plate having edges to cooperate with said dog to permit its nose to enter and recede from said holes, the strip and nose causing the dog and slide member to travel with the strip in one direction, and means to operate the slide and dog in another direction.

2. Means for aligning a perforated strip of metal as set forth in claim 1, in which one of the edges inclines toward the strip to cause the dog to advance its nose into holes in the strip, and another of said edges causes the dog to retain its nose in the said holes during travel of the strip and to release the dog.

3. Means for aligning a perforated strip of metal as set forth in claim 1, in which one of the edges inclines toward the strip to cause the dog to advance its nose into holes in the strip, another of said edges causes the dog to retain its nose in the said holes during travel of the strip and to release the dog, and other of said edges permit complete with-

drawal of said nose from holes in the strip and guide the dog to the first named inclined edge.

4. Means for aligning a perforated metal strip while traveling comprising a slide member, guiding means therefor, a dog movably carried by said member and provided with a nose to enter holes in said strip to align the latter, a plate having edges to cooperate with said dog to permit its nose to enter and recede from said holes, the strip and nose causing the dog and slide member to travel with it in one direction, means to operate the slide and dog in another direction, one of the edges inclining toward the strip to cause the dog to advance its nose into holes in the strip, another of said edges causing the dog to retain its nose in said holes during travel of the strip and to release the dog, and another of said edges permitting complete withdrawal of said nose from holes in the strip and guide the dog to the first named inclined edge, and a finger to cooperate with the dog to cause it to travel along the last named edge.

5. Means for aligning a perforated metal strip set forth in claim 4, provided with another finger cooperative with the dog to return it into operative relation to the said inclined edge.

6. Means for aligning a perforated strip of metal while traveling comprising a slide member, guiding means therefor, a dog movably carried by said member and provided with a nose to enter holes in said strip to align the latter, a plate having edges to cooperate with said dog to permit its nose to enter and recede from said holes, the strip and nose causing the dog and slide member to travel with it in one direction, means to operate the slide and dog in another direction, and a surface to operate the dog to force its nose out through the holes in the strip toward the termination of the travel of the dog with the strip.

7. Means for aligning a perforated strip of metal as set forth in claim 6, said surface being on the side of the strip opposite the dog in position to be encountered by its nose to force it along the holes in the strip.

8. Means for aligning a perforated strip of metal while traveling comprising means to propel the strip, a slide member, guiding means therefor, a dog movably carried by said member and provided with a nose to enter holes in said strip while it is traveling to support and align the latter, the dog having a projection, a plate having a recess provided with edges cooperative with said projection, one of said edges being inclined to cause the nose to enter holes in the strip for travel of the dog by and with the strip, an adjacent edge being substantially parallel with the strip to cause retention of the nose in the holes of the strip, another edge being inclined away from the strip to cause com-

plete withdrawal of the nose from the strip, and another edge in cooperation with said projection retaining the dog withdrawn from the strip, the last edge coinciding with the first named edge to permit the projection to return thereto, and means to operate the slide and dog in a direction opposite to their travel with the strip.

9. Means for aligning a perforated strip of metal while traveling comprising a slide member, a guiding means therefor, a dog movably carried by said member and provided with a nose to enter holes in said strip to align the latter, the dog having a projection, a plate having a recess provided with edges cooperative with said projection, one of said edges being inclined to cause the nose to enter holes in the strip for travel of the dog with the strip, an adjacent edge being substantially parallel with the strip to cause retention of the nose in the holes of the strip, another edge being inclined away from the strip to cause complete withdrawal of the nose from the strip, and another edge in cooperation with said projection retaining the dog withdrawn from the strip, the last edge coinciding with the first named edge to permit the projection to return thereto, means to operate the slide and dog in a direction opposite to their travel with the strip, and a finger to operate the projection to completely withdraw the nose from the strip.

10. Means for aligning a perforated strip of metal as set forth in claim 9, provided with another finger to be engaged by the projection to cause operation of the dog for entry of its nose in holes in the strip.

CONRAD SCHUMACHER.
